UNITED STATES PATENT OFFICE.

FREDERICK P. RENNEBURG, OF BALTIMORE, MARYLAND.

PRESS.

1,005,472.

Specification of Letters Patent. Patented Oct. 10, 1911.

Application filed February 14, 1911. Serial No. 608,593.

To all whom it may concern:

Be it known that I, FREDERICK P. RENNEBURG, a citizen of the United States, residing at Baltimore, in the State of Maryland, have invented certain new and useful Improvements in Presses, of which the following is a specification.

This invention relates to improvements in presses and has particular reference to devices of this character employed in extracting the oil from fish.

The invention consists in the improved construction, combination and arrangement of parts hereinafter set forth and particularly pointed out in the claims.

The invention is illustrated in the accompanying drawings, wherein,

Figure 1, shows the machine in perspective. Fig. 2, is a top plan view of the feed-in end of the machine. Fig. 3, is a vertical longitudinal section through the larger feed-in end of the machine. Fig. 4, is a top plan view of the smaller discharge-end of the machine. Fig. 5 is a vertical longitudinal section and partly side elevation of the machine at the discharge end. Fig. 6, is a vertical cross-sectional elevation through the machine taken on the line 6-6 of Fig. 3 and looking toward the feed hopper. Fig. 7, is an enlarged cross-sectional detail through the slatted upper cylinder member. Fig. 8, is a cross-sectional detail through one of the arch-shaped bars to which the cylinder slats are secured. Fig. 9, is a perspective detail of one of the slat securing bolts, and Figs. 10 and 11, are end views and side elevation respectively of a pair of adjacent slats and the bolts that secure them together and to the arch-shaped bars.

Referring to the drawings, the numeral 1, designates two parallel side walls of the machine of structural steel which are connected by a bearing plate, 2, at one end and a suitable bracket plate, 3, at the opposite end, all forming a rectangular structure having sufficient strength and rigidity for the use to which it is to be put. The said two walls, 1, have a straight bottom from one end to the other, but these walls at their ends are vertically higher than the part of the wall intermediate of said ends. This construction affords useful results that will be presently described.

The bearing plate, 2, at the one end of the two side walls and the bracket plate, 3,

at the opposite end are provided with bearings, 4, and 5, respectively, which sustain the opposite ends of a screw-conveyer shaft, 6. This conveyer shaft has a spiral thread, 7, which is larger at one end than the other and which is gradually reduced in diameter from the larger to the smaller end. It may be remarked that the shaft, 6, and the spiral conveyer, 7, constitute one integral metal structure, which part alone weighs six thousand pounds in a fish-press like that shown in the drawing. In a large and heavy machine of this character the shaft, 6, of the heavy spiral conveyer must have its end bearings, 4, and, 5, supported by a mass of metal that will afford the requisite stability and rigidity; for this reason I have contrived that the ends of the side walls, 1, shall be high enough to serve this object and at the same time I have made the horizontal top edge of the side walls intermediate of the ends depressed or lower than the ends in order to avoid hindrance to the outward side-swinging of the link-bars, 32, presently to be described. The conveyer-shaft at the larger end is provided with a hard metal plug, 8, against which the inner end of a thrust bolt, 9, impinges. The bolt passes through a head, 10, fixed on the bearing plate, 2, and carries a threaded head, 11, at the inner side of the head, 10, and a lock-nut, 12, at the outer side of said head whereby the longitudinal movement of the bolt will effect a corresponding adjustment of the conveyer, as will be presently more fully explained.

The spiral conveyer is inclosed in a slatted shell of improved construction which will now be described. At intervals between the ends the side walls, 1, sustain a series of lower semi-cylindric bracket supports, 13, each of which is of a different diameter than those at either side of it so that the supports will be from the receiving end where they are larger to the discharge end where they are smallest—the upper edges, 14, however of all the lower supports are in the same horizontal plane. These bracket supports have flanges, 15, which seat against and are bolted to the side walls, 1, as may be read in Figs. 1, 2 and 4 of the drawings. Each bracket support also has a flange, 16, at its inner edge for a purpose to be explained.

In order to form a slatted casing about the screw conveyer I provide a series of longitudinally-extending slats or bars, 17, which,

it will be noted by reference to Figs. 7, 10 and 11, are tapered in cross-section,—being wider at their inner faces, 18, than at their outer faces, 19. The slats or bars are arranged longitudinally and in pairs side-by-side with the broader inner surfaces comparatively close together and thereby produce a series of V-shaped or tapered longitudinal slots, 20. At intervals between their inner ends the slats or bars are secured together in pairs by means of bolts, 21, having tapered heads, 22, each with a perforation, 23, therein, as seen in Fig. 9. The tapered head of the bolt is inserted in the tapered longitudinal slot, 20, between the bars and a rivet or equivalent fastening 24, is passed crosswise through the bars and also through the perforation, 23, of the bolt head. By this means the bolt heads, 22, serve to secure the slats together and also to hold them in a spaced-apart position. A nut, 25, is provided on the outer end of each bolt, 21, and by reference to Fig. 8, it will be seen that one side of the nut will seat on the flange, 16, of the bracket support.

A semi-circular bar, 26, is placed around the outer side of the slats or bars and against the opposite side of the bolts, 21. The cross-sectional area of the bar being such that its outer curved surface will be parallel and flush with the flange, 16, of the bracket support and thereby the bolts, 21, have position in a slot formed between the said flange, 16, and the semi-circular bar, 26. By means of this construction the outer side of the nut, 25, will seat on the bar, 26, while the inner side of said nut will seat on the flange, 16, consequently the slats or bars, 17, will be drawn outward and held against the arched or curved faces of the bracket supports. In order to prevent displacement of the bar, 26, I provide a clip bar, 27, which has its opposite ends, 28, turned outwardly, as clearly seen in Figs. 7 and 8. This clip bar seats on the longitudinal slot, 20, between the slats and extends across the inner surface of the bracket supports, and one out-turned end projects at the outer side of the bar, 26, while the other out-turned end projects behind the wall of the rigid bracket support. By this means the bar, 26, cannot move laterally and away from the support and the bolt head, 25, is sustained at opposite sides.

In practice I have found it advantageous to form the slatted shell in two longitudinal sections, an upper and a lower section, and consequently the slats or bars extend only from one end to the other of the particular section of which it is a part. In the present instance the machine is shown as having three sections, 29, 30, and, 31, respectively,—the section, 29, being the largest and the section, 31, the smallest. When the slats or bars have been secured to the series of lower supports, 13, they will form the lower half

of the slatted shell on which the upper half of the shell will be placed. Each lower support, 13, is provided with a bifurcated link bar, 32, which straddles the support and has its lower end pivotally connected thereto by means of a pin, 33, that extends through both legs of the bar and also through the support. The upper end of each link bar is provided with a head, 34, having a central vertical and threaded opening therein through which a set bolt, 35, extends all for a purpose presently to be explained. The upper sections of the shell are formed substantially like the lower sections so far as the slats or bars are concerned but these latter are not secured to brackets that are carried by the side walls but are partly circled at intervals by arched bars, 36, having squared shoulders, 37, at opposite sides, as clearly seen in Fig. 6. These arched bars have the lateral flanges, 16, and semi-circular bars, 26, the same as described in connection with the lower bracket supports and the manner of securing the bars to the arched bars is precisely the same as in the lower sections. The upper sections however are provided at opposite sides with horizontal flanged bars, 38, which form the base of the upper arch and which fit in lower edge notches, 39, in the said arched bars to which they are secured by suitable fastenings, 40, as seen in broken lines in Fig. 7. The upper sections are seated on top of the lower bracket supports, 13, and the bifurcated link bars, 32, are swung over the shoulders, 37, of the arched bars and the set bolts, 35, are screwed down on said shoulders to rigidly hold the upper sections down on the lower bracket supports. In order to facilitate the operation of the link bars and permit ready access to the upper ends of said bars, I have provided a drop or depression, 41, in the upper edge of the side walls as clearly seen in Fig. 1.

From the foregoing explanation it is to be understood that the spirally-threaded conveyor is inclosed from end to end by the upper and lower slatted sections which taper so as to conform to and snugly surround the screw,—the slats or bars being spaced slightly at their inner surfaces which spaces increase in width from the inner toward the outer surfaces. A suitable slatted hopper, 42, is provided at the large end of the casing or shell through which the materials to be treated by the machine are fed to the interior of the casing where the screw advances or forces it toward the smaller discharge end. At the smaller end of the screw the machine is provided with a circular plate, 43, having an opening, 44, through which the screw shaft, 6, extends and the material forced from the smallest shell section, 31, passes through the opening, 44, in said plate over the discharge outlet, 45.

In practice it has been found that the compressed material at the time it passes from the smaller end of the casing is often compressed to such an extent that it forms a compact mass and clings about the shaft instead of breaking away and dropping down through the outlet, 45, and thereby choking up the machine at the outlet. To overcome this I provide a cutter, 46, in front of the outlet, 44, so that the material will be forced against said cutter and sufficiently divided to cause it to break loose from the shaft 6, and drop. In the present instance the cutter is secured about the shaft, 6, by means of a clamp, 47, and both cutters and clamp turn with said shaft. To drive the screw I provide a large gear, 48, on the end of the shaft, 6, beyond the bearing, 5, which gear meshes with and is driven by a pinion, 49, in a horizontal shaft, 50, that is sustained in suitable bearings above the side walls of the machine. A comparatively large gear, 51, is also carried on the shaft, 50, which meshes with and is driven by a pinion, 52, on another horizontal shaft, 53. A driving pulley, 54, is also carried on this latter shaft which in practice is driven by a belt, not shown.

It is believed to be obvious that the materials in traveling through the tapered casting or shell will be more and more compressed and any fluids such as water and oils will be pressed out and flow through the longitudinal grooves and drip beneath the shell where they will be caught and conveyed off for further treatment. The longitudinal grooves being wider at their outer discharge side than at their inner sides will not become clogged because the small particles of materials that will pass into the grooves will readily pass out.

Having thus described my invention what I claim and desire to secure by Letters Patent is,—

- 45 1. In a press of the character described the combination with a tapered screw, of means for rotating the same; a plurality of upper and lower semi-circular bars each having a curved flange; longitudinal bars of a V-shape in cross-section and arranged side by side; bolts having tapered heads to enter between and engage the longitudinal bars,—said bolts engaging the curved flanges of the semi-circular bars.
- 50 2. In a press of the character described the combination with a tapered screw, of

means for rotating the same; a plurality of upper and lower semi-circular bars each having a curved flange; longitudinal bars of a V-shape in cross-section and arranged side by side; bolts having tapered heads to enter between and engage the longitudinal bars,—said bolts having nuts which engage the curved flanges of the semi-circular bars; a curved bar extending around the outer sides of the longitudinal bars and contacting with said bolts and means for securing said curved bars to the semi-circular bars.

3. In a press of the character described, the combination with a spiral revoluble conveyer of a stationary shell inclosing said spiral conveyer and having longitudinal bars separated by narrow spaces, curved bars around the outer sides of the longitudinal bars, and bolts whose heads are entered in said narrow spaces and engage the longitudinal bars, and the outer ends of said bolts having nuts that engage the said outer curved bars.

4. In a press of the character described, the combination with a spiral revoluble conveyer of a stationary shell inclosing said spiral conveyer and having longitudinal bars separated by narrow spaces, two parallel curved bars around the outer side of the said longitudinal bars and forming between the two a curved slot, bolts whose heads are in said narrow spaces and engage the longitudinal bars and said bolts having threaded shanks which have position in said curved slot, and nuts on the bolts and bearing on both parallel curved bars.

5. In a press of the character described the combination of two side-walls having high ends and intermediate of said ends each wall having a top edge that is depressed or lower than said ends; a tapered screw between said two side-walls and turning in bearings which are secured between said high ends; upper shell sections over said tapered screw; and vertically-positioned link-bars that confine said upper shell sections and whose lower ends are pivoted and which swing outwardly over the said depressed or lower part of the side-walls.

In testimony whereof I affix my signature in presence of two witnesses.

FREDERICK P. RENNEBURG.
